UNITED STATES PATENT OFFICE.

JOHN G. HICKS AND JOHN McGREER, OF CHICAGO, ILLINOIS.

DESIGN FOR A STATUETTE.

SPECIFICATION forming part of Design No. 28,054, dated December 14, 1897.

Application filed September 22, 1897. Serial No. 652,655. Term of patent 3½ years.

To all whom it may concern:

Be it known that we, JOHN G. HICKS and JOHN McGREER, citizens of the United States, residing at Chicago, in the county of Cook and State of Illinois, have invented and produced a new, useful, and original Design for Statuettes, of which the following is a specification, reference being had to the accompanying drawing.

10 The drawing shows a front elevation of our design for a statuette.

The drawing represents a negro baby in a standing position and attired in a full long dress having long sleeves, the arms being

raised. On the head is worn a hood or bonnet 15 having an enlarged border around the front and tied with a large bow under the chin. The whole presents the grotesque appearance of an over-dressed child, characteristic of the negro race.

20 What we claim is—

The design for a statuette as herein shown and described.

JOHN G. HICKS.
JOHN McGREER.
